UNITED STATES PATENT OFFICE.

FRANK B. MILLER, OF NORWALK, OHIO.

DESIGN FOR A TOY OR ARTICLE OF SIMILAR NATURE.

Application filed June 2, 1927. Serial No. 22,281. Term of patent 7 years.

To all whom it may concern:

Be it known that I, FRANK B. MILLER, a citizen of the United States, residing at Norwalk, in the county of Huron and State of Ohio, have invented a new, original, and ornamental Design for a Toy or Article of Similar Nature, of which the following is a specification, reference being had to the accompanying drawing, forming a part thereof.

In the drawing:

Fig. 1 is a side elevational view of a toy, or article of similar nature showing an embodiment of my new design; and

Fig. 2 is a front elevational view of the toy, or article of similar nature shown in Fig. 1.

I claim:

The ornamental design for a toy or article of similar nature substantially as shown.

In testimony whereof I affix my signature.

FRANK B. MILLER.
